Primary Examiner — Austin Murphy*(74) Attorney, Agent, or Firm* — Polsinelli PC(57) **CLAIM**

I claim the ornamental design for a mouse, as shown and described.

DESCRIPTION

FIG. 1 is a perspective view of a mouse;
 FIG. 2 is a front elevational view thereof;
 FIG. 3 is a rear elevational view thereof;
 FIG. 4 is a right side elevational view thereof;
 FIG. 5 is a left side elevational view thereof;
 FIG. 6 is a top plan view thereof; and,
 FIG. 7 is a bottom plan view thereof.

Dashed broken lines are for illustrating portions of the mouse which form no part of the claimed design.

Dashed-dot broken lines are for illustrating unclaimed areas of the mouse; the dashed-dot line forms no part of the claimed design.

1 Claim, 7 Drawing Sheets(56)
